Fig. 6

Fig. 7

Fig. 8

Fig. 9

Fig. 10

Fig. 11

FIG. 1 is a top plan view of a tape recorder showing my new design;

FIG. 2 is a bottom view,

FIG. 3 is a right side elevational view,

FIG. 4 is a left side elevational view,

FIG. 5 is a front elevational view,

FIG. 6 is a rear elevational view,

FIG. 7 is a top plan view without cover,

FIG. 8 is a bottom view of the cover,

FIG. 9 is a right side elevational view without cover,

FIG. 10 is an exploded right side perspective view, to a reduced scale, with the cover removed; and

FIG. 11 is a left side perspective view thereof, to a reduced scale.

Portions of the cover are diagonally lined to indicate transparency.

I claim:

The ornamental design for a tape recorder, as shown and described.
